UNITED STATES PATENT OFFICE.

RADFORD STOCKBRIDGE, OF WORCESTER, MASSACHUSETTS, ASSIGNOR OF ONE-HALF
TO ARTHUR W. BEAMAN, OF WORCESTER, MASSACHUSETTS.

DRIVING MECHANISM FOR SHAPING-MACHINES.

1,109,188.

Specification of Letters Patent.

Patented Sept. 1, 1914.

Application filed April 2, 1913. Serial No. 758,430.

To all whom it may concern:

Be it known that I, RADFORD STOCKBRIDGE, a citizen of the United States, residing at Worcester, in the county of Worcester and State of Massachusetts, have invented a new and useful Driving Mechanism for Shaping-Machines, of which the following is a specification.

This invention relates to the mechanism for driving the ram of a shaping machine, although the principle is capable of general use where rotary motion is to be converted into reciprocating motion.

The principal objects of the invention are to provide a support for the driving crank of a shaping machine of a more firm and stable character than has been the case heretofore so as to eliminate chattering on long cuts and to do away with all possibility of breaking of the hub and especially to provide a large bearing surface for this purpose on each side of the point at which power is applied which shall be suitable for the plain crank or the two piece crank style of shaping machine; also to provide an improved lubricating device therefor.

The invention also involves improvements in combinations of parts and in details of construction as will appear hereinafter.

Reference is to be had to the accompanying drawings in which—

Figure 1 is an elevation of a shaping machine with the interior shown in section on a vertical plane through the center of the driving gear; Fig. 2 is a vertical sectional view on enlarged scale on the line 2—2 of Fig. 1; Fig. 3 is a sectional view on the line 3—3 of Fig. 2; Fig. 4 is a front elevation of the crank plate and ring bearing; Fig. 5 is an elevation partly in section taken along the line 5—5 in Fig. 4, the eccentric ring being omitted; and, Fig. 6 is a front elevation of the driving gear and eccentric ring with their sliding connections.

The invention is shown as applied to a shaping machine of the type set forth in my previous Patents No. 807,216 granted December 12, 1905, and No. 979,589 granted December 27, 1910. Accordingly the drawings show the invention as applied to a construction involving the frame-work having a column 1 with horizontal top ways 2 for the reciprocating ram 3. It will be understood of course that the usual feeding device indicated in a general way by the nu-

meral 5 is intended to be used but does not constitute a part of this invention. The frame, however, is provided with a column 1 having a hub 11^a on one side which is bored out to receive a box 10. On the inside 60 of the column is a flange which is bored out to receive the fixed crank bearing 30. This flange also forms a guard for the gear 7, and protects it from chips and dirt. The gear 7 is preferably operated in the manner 65 described in my above mentioned patents. This gear is provided with a hub 8 journaled in the box 10 and rotating on the outside of a hub 9 which is held at its outer 70 end by a flange through which the bolts 11 70 pass into the box 10.

On the inner end of the hub 9 is a fixed eccentric 12 having a rotating eccentric ring 13 which is rotated by a block 14 sliding in radial ways 15 in the driving gear 7. This 75 eccentric ring has a stud 16 for connecting it with the block 14 and it also carries a stud 17 on the opposite side upon which is pivotally mounted a block 18 sliding radially in a slot 19 in the rotary crank plate 30 20. This crank plate is cylindrical in form and fits inside the flange of the gear 7 projecting beyond it at one side. With this exception and the arrangement of the hubs these parts are shown in my patents previously mentioned.

The crank plate 20 and gear 7 constitute a two piece crank but the invention is applicable to the one piece crank style of shaping machine. The crank plate is provided 90 with a long hub 21 which is journaled within the fixed hub 9. It is also provided with radial ways 22 for the block 23 which is capable of adjustment along the ways by a screw 24 mounted on the crank plate 20 95 and adapted to be turned for the adjustment of the block by means of a series of gears or pinions connected with a spindle 25 and operated by a wrench, as described in my above mentioned patents. The block 23 100 operates the ram 3 in the manner described in said patents.

According to the present invention, the driving crank is supported at one side by the hub 9 and on the other side at its extreme edge by the fixed bearing 30 in the column. The latter may be secured to the framework by means of screws or the like. In this case the frame is bored and bushed. The inner edge of the flange and teeth of the driving 110

gear are spaced from the vertical flat surface of this bearing 30, but it projects over them, and keeps out dirt and chips. The crank plate 20 is flanged out at 31 beyond the edge of the driving gear so as to furnish a surface for engagement in the bearing 30. In this way it will be seen that the fixed bearing 30 constitutes a firm and rigid support for the driving crank and assists in 10 steadyng it. The power is applied to the crank between this support and the hub 8.

For the purpose of securing an adequate lubrication of the bearing 30, an oil receptacle 34 is provided at the bottom of the 15 frame and in it is arranged a socket 35 for receiving a supporting frame 36 which is pressed up by a spring 37 resting on a removable plug 38 in the bottom. On this spring-supported frame 36 is a smooth-surfaced wheel 39 free to rotate on a shaft 20 thereon.

The oil receptacle 34 is filled with oil sufficiently to come above the bottom of the wheel 34. Above the wheel is a second 25 wheel 40 which is mounted to rotate freely on a shaft in a frame 41 supported by springs 42 resting on sockets 43 on the bearing 30. The bearing 30 is provided with a recess 44 for receiving these parts and the springs 42 and 37 press the wheel 40 up 30 against the surface of the rotating crank plate 20. It will be seen, therefore, that the lubricant is constantly fed to the surface of this crank plate so as to be distributed 35 around the surface of the bearing 30. Moreover, it will be seen that any excess of lubricant will run down the crank plate and some of it will pass back into the space 44 and directly into the oil receptacle. That 40 which runs down the outer face of the crank plate at the left in Fig. 1 will drain down along a groove 46 in the face of the ring 30 until it passes through the openings 46^a into the receptacle 34. Additional lubrication is provided by a circumferential recess 45 50 and lubricating ring 51 resting on the hub 8 of the driving gear.

By this invention the hub of the driving crank is supported on one side and the edge 50 is supported firmly on the other side so that the chattering of the gear on long cuts is avoided and the possibility of the breaking of the hub is practically eliminated. At the same time the parts are kept supplied with 55 a constant flow of oil and as long as the

receptacles 34 and 50 are supplied with the same, there is no danger of any of these parts running dry.

Although I have illustrated and described only a single embodiment of the invention 60 and shown it as applied to a single type of shaping machine, I am aware of the fact that the invention can be carried out with modifications in details of construction and applied to other types of machines particularly the plain crank type of shaping machines without departing from the scope of the invention as expressed in the claims. Therefore, I do not wish to be limited to all 65 the details of construction herein shown and 70 described, but

What I do claim is:—

1. A shaping machine having in combination a driving crank plate having a cylindrical hub, and a circumferential external bearing surface, a column, a bearing mounted on said column and supporting said hub and a fixed bearing ring mounted in the column and supporting the crank plate on its circumferential external bearing surface. 75
2. In a device of the class described, the combination of a driving gear having a flange projecting therefrom on one side, a crank plate mounted upon a fixed hub and freely rotatable within but projecting beyond said flange, and a fixed bearing ring having its inner surface surrounding and engaging the outer surface of the crank plate. 85
3. In a shaping machine, the combination 90 of a driving gear having a flange projecting therefrom on one side, a crank plate freely rotatable within and projecting beyond said flange, a fixed bearing ring having a cylindrical surface engaging the outer 95 surface of the crank plate, and a lubricating device, said ring bearing being arranged in vertical position and having an opening therethrough at the bottom thereof to permit liquid lubricant to be applied to the 100 outer surface of said crank plate by said lubricating device.

In testimony whereof I have hereunto set my hand, in the presence of two subscribing witnesses.

RADFORD STOCKBRIDGE.
